Patented Nov. 1, 1921.

UNITED STATES PATENT OFFICE.

RANDOLPH MADISON, OF PETERSBURG, VIRGINIA.

LOCKING DEVICE.

1,395,721.

Specification of Letters Patent.

Patented Nov. 1, 1921.

Application filed March 2, 1921. Serial No. 449,019.

To all whom it may concern:

Be it known that I, RANDOLPH MADISON, a citizen of the United States, residing at Petersburg, in the county of Dinwiddie and 5 State of Virginia, have invented certain new and useful Improvements in Locking Devices, of which the following is a specification, reference being had to the accompanying drawings.

10 This invention relates to certain improvements in locking devices and has relation more particularly to a device of this general character especially designed and adapted for use in connection with a wardrobe trunk, 15 and it is an object of the invention to provide a novel and improved locking device which serves effectually to maintain the drawers of a wardrobe trunk in closed position to hold the same against undue vibration when the trunk is in transit and also to 20 hold said drawers against opening movement when the lid or top of the trunk is open.

The invention consists in the details of 25 construction and in the combination and arrangement of the several parts of my improved locking device whereby certain important advantages are attained and the device rendered simpler, less expensive and 30 otherwise more convenient and advantageous for use, as will be hereinafter more fully set forth.

The novel features of my invention will 35 hereinafter be definitely claimed.

In order that my invention may be the 40 better understood, I will now proceed to describe the same with reference to the accompanying drawings, wherein:

Figure 1 is a view in perspective illustrating a wardrobe trunk having applied thereto a locking device constructed in accordance with an embodiment of my invention;

Fig. 2 is an enlarged fragmentary view in elevation illustrating in detail the operative 45 connection between adjacent locking strips, said strips being in locking position;

Fig. 3 is a fragmentary sectional view taken substantially on the line 3-3 of Fig. 2;

Fig. 4 is a view similar to Fig. 3, showing the locking strips in open position; and Fig. 5 is a view in plan of a pair of coacting segmental gears.

As disclosed in the accompanying drawings, T denotes a wardrobe trunk of a con-

ventional type and which has slidably supported therein the drawers D, said drawers moving outwardly of the trunk T when the lid or cover L is in open position.

Hingedly connected with the longitudinal 60 marginal portions of the trunk T at the open or top face thereof are the elongated strips 1, each of said strips being of a length substantially coextensive with the interior length of the trunk, so that, when the strips 65 are in their closed or inward position, they will overlie and contact with the drawers D to hold the same against undue vibration and also against outward or opening movement.

Also hingedly connected with the outer marginal portion of the trunk T at one end thereof is the strip 2 which, when in its closed or inner position, has contact with the adjacent drawer D to provide means to 75 further hold said drawer against outward movement.

The strips 1 and 2 are held in applied position by the hinges 3 and the hinges at the adjacent ends of the strips 1 and 2 80 have their pintles 4 extended. Secured to the extended portion of each of said pintles 4 is a segmental gear 5 in mesh one with the other so that, upon movement of a strip 1 or the strip 2, all of said strips 1 and 2 85 will move in unison and in the same general direction.

In order that the strips 1 and 2, when in their inner or closed position, may have proper coaction with the drawers D, the adjacent ends of the strips 1 and 2 are beveled so that, when in their closed or inner positions, the strips 1 will offer no obstruction to the strip 2 and vice versa.

Carried by one of the strips, and preferably by the strip 2, is any preferred type of lock mechanism, generally indicated at 6 in Fig. 1, and which mechanism coacts in any desired manner with the trunk T to lock the strips 1 and 2 at their inner or 100 closed position, so that, when the cover or lid L is open, the strips 1 and 2 serve to maintain the drawers D against opening movement by unauthorized persons and which is of particular advantage in hotels 105 or the like to reduce the possibility of petty theft.

By locking the strips 1 and 2 in their inner or closed position, the drawers D are held against undue vibration when the trunk 110

T is in transit and this in itself is of importance and advantage.

From the foregoing description it is thought to be obvious that a locking device 5 constructed in accordance with my invention is particularly well adapted for use by reason of the convenience and facility with which it may be assembled and operated, and it will also be obvious that my invention 10 is susceptible of some change and modification without departing from the principles and spirit thereof and for this reason I do not wish to be understood as limiting myself to the precise arrangement and formation 15 of the several parts herein shown in carrying out my invention in practice except as hereinafter claimed.

I claim:

1. In combination with a container having 20 a compartment, a plurality of drawers slidably mounted in the compartment, locking strips hingedly connected along the sides and one end of the compartment, said strips being arranged to swing into and out of the 25 path of travel of the drawers, and operative connection between adjacent strips whereby all of said strips have movement in unison and in the same general direction.

2. In combination with a container hav-

ing a compartment, a plurality of drawers 30 slidably mounted in the compartment, locking strips hingedly connected along the sides and one end of the compartment, said strips being arranged to swing into and out of the 35 path of travel of the drawers, operative connection between adjacent strips whereby all of said strips have movement in unison and in the same general direction, and means for locking said strips against swinging movement in a direction out of the path of travel 40 of the drawers.

3. In combination with a container having a compartment, a plurality of drawers 45 slidably mounted in the compartment, locking strips hingedly connected along the sides and one end of the compartment, said strips being arranged to swing into and out of the path of travel of the drawers, operative connection between adjacent strips whereby all of said strips have movement in unison and 50 in the same general direction, and means carried by one of the strips for locking said strips against swinging movement in a direction out of the path of travel of the 55 drawers.

In testimony whereof I hereunto affix my signature.

RANDOLPH MADISON.
